DESIGN FOR A HANDLE FOR A BAR SPIGOT OR SIMILAR ARTICLE

Jacob E. Newman, Pittsburgh, Pa.

Application August 26, 1935, Serial No. 58,296

Term of patent 7 years

To all whom it may concern:

Be it known that I, Jacob E. Newman, a citizen of the United States, residing at Pittsburgh, in the county of Allegheny and State of Pennsylvania, have invented a new, original, and ornamental Design for a Handle for a Bar Spigot or Similar Article, of which the following is a specification, reference being had to the accompanying drawing, forming part thereof.

I claim:

The ornamental design for a handle for a bar spigot or similar article, substantially as shown.

JACOB E. NEWMAN.
